[57] **CLAIM**

The ornamental design for a valve for equalizing pressure resulting from explosions or blasts, as shown and described.

DESCRIPTION

FIG. 1 is a front perspective view of a valve for equalizing pressure resulting from explosions or blasts showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a side elevational view, the opposite side being a mirror image thereof;

FIG. 7 is a front perspective view of a second embodiment thereof as shown in FIG. 1;

FIG. 8 is a rear perspective view thereof;

FIG. 9 is a front elevational view thereof;

FIG. 10 is a right side elevational view thereof;

FIG. 11 is a rear elevational view thereof; and

FIG. 12 is a left side elevational view thereof.

FIG. 1

FIG. 2
